(57) **CLAIM**

I claim the ornamental design for a toothbrush handle, as shown and described.

DESCRIPTION

FIG. 1 is a top, front isometric view of a toothbrush handle, showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a bottom, rear isometric view thereof.

The broken line showing of the toothbrush head depicts environmental structure and forms no part of the claimed design. All other broken lines in the drawings depict portions of the toothbrush handle that form on part of the claimed design.
